UNITED STATES PATENT OFFICE.

GEORGE WATKINSON, OF NEW HAVEN, CONNECTICUT, ASSIGNOR TO THE
L. CANDEE & CO.

RUBBER BOOT.

SPECIFICATION forming part of Letters Patent No. 223,783, dated January 20, 1880.

Application filed December 3, 1879.

To all whom it may concern:

Be it known that I, GEO. WATKINSON, of New Haven, in the county of New Haven and State of Connecticut, have invented a new 5 Improvement in India-Rubber Boots; and I do hereby declare the following, when taken in connection with the accompanying drawing and the letters of reference marked thereon, to be a full, clear, and exact description of the 10 same, and which said drawing constitutes part of this specification, and represents a sectional side view.

This invention relates to an improvement in the method of lining india-rubber boots.

15 In the usual construction the felt or woolly surface-lining extends throughout the interior of the leg and foot. In the wear of the boot this lining acts upon the heel of the stocking, and soon cuts or wears it away, to the annoyance and discomfort of the wearer. To obviate this difficulty, leather or similar material has been introduced to form the lining around the heel; but the process of vulcanization necessary to complete the boot tends to harden 20 and so affect the leather as to cause it to wrinkle and crack. Again, the leather will easily absorb the moisture produced by perspiration, and cause the heel to stick and make it difficult for the wearer to remove his 25 boots—another source of great annoyance to the wearer.

The object of this invention is to overcome these difficulties; and it consists in the introduction of an india-rubber lining around the 30 heel portion or counter of the boot, either inside the usual lining, or the lining cut away to the extent of such rubber counter-lining, and as fully hereinafter described.

The general form and make-up of the boot 35 is the same as that in general use, too well

known to require detailed description in this specification.

A represents the lining, made from felt or other woolly-surfaced material, and extends over the interior surface of the boot, but preferably is cut away at the counter, as indicated 45 by the plain surface *a*.

The part *a* represents the counter-lining, made from india-rubber. In making up the boot this india-rubber counter-lining is placed 50 around the heel part of the form and next to it, and its lower edge turned down onto the insole, which has been first placed upon the last, and, as seen in the drawing, the placing of the other parts upon the form and the finishing of 55 the boot are proceeded with in the usual manner.

This construction places around the heel a lining which is not injured by the vulcanizing process, but is very smooth, and the moisture 60 unavoidably produced in wearing the boot tends to prevent the heel from sticking, instead of to make it stick, as in the case of leather or material other than rubber, and also avoids the usual wear of the stocking. 65

From the foregoing it will be seen that I do not broadly claim lining the counter of the boot with a material different from the lining of the rest of the boot; but

What I do claim is—

As an improved article of manufacture, a rubber boot provided with an india-rubber counter-lining extending around the inner heel portion, as shown and described, and for the purpose specified.

GEORGE WATKINSON.
